PROCESS FOR PRODUCING A DETERGENT MIXTURE

Pieter L. Kooijman, Ferdinand A. Doorman, and Cornelis Kortland, all of Amsterdam, Netherlands, assignors to Shell Oil Company, a corporation of Delaware

No Drawing. Application September 10, 1956

Serial No. 608,708

Claims priority, application Netherlands September 16, 1955

11 Claims. (Cl. 252—161)

This invention relates to the manufacture of mixed synthetic detergents containing alkyl aryl sulfonates together with secondary alkyl sulfate salts as active detergent components. It deals with a new and especially advantageous process for producing mixed detergents of this kind and provides novel detergent compositions having improved properties.

Mixtures of alkyl aryl sulfonate detergents with alkyl sulfates have been previously proposed as useful for special purposes. Thus Lewis patent, U.S. 2,631,980, claims the use of monoalkylbenzene sulfonates having about 12 to 15 carbon atoms in the alkyl group with alkyl sulfates of 8 to 12 carbon atoms per molecule in amounts of 10 to 30% of their combined weight as non-caking detergent compositions. Such mixtures have, hitherto, been prepared by separately synthesizing the two types of detergents and thereafter blending them with or without added builders.

Alkyl aryl sulfonate detergents and secondary alkyl sulfate detergents have both been manufactured on a large scale for a long time. The alkyl aryl sulfonates are customarily made by sulfonating the corresponding alkylated aromatic hydrocarbon, for example, alkylation products of benzene, toluene, naphthalene, or the like, with olefins using alkylation catalysts such as sulfuric acid, hydrogen fluoride, etc. The olefins used in commercial practice are mixtures with varying numbers of carbon atoms, those averaging from about 12 to about 15 carbon atoms per molecule having been frequently recommended as most desirable. Olefins which are suitable for the alkylation can be obtained, for example, by vapor phase cracking of paraffin wax or of refined heavy catalytically cracked cycle oil or, the like, or more usually by polymerizing lower olefins such, for example, as propylene the tetramer fraction of which has been frequently used. An excess of the aromatic hydrocarbon is usually used in the alkylation and after completion of the reaction the excess is distilled off from the crude alkylate. The crude alkylate must then be fractionated to remove impurities which are not sulfonated in the following sulfonation step. Suitable methods for carrying out the sulfonation of the distilled alkylate are described, for example, in U.S. Patents 2,567,854 and 2,676,185, after which the alkyl aryl monosulfonic acids obtained are neutralized, for example, with sodium hydroxide or sodium carbonate or other base to form the desired alkyl aryl sulfonate detergent.

It has been found that in order to obtain alkyl aryl sulfonates having the surface active properties, particularly the detergency and sudsing power, necessary for commercial use as a detergent, the alkyl aryl hydrocarbon must meet rigid requirements as to purity. Thus it is essential in present practice to use alkylates having a sulfonatability of at least 96% and more advantageously about 98% if an alkyl aryl sulfonate having satisfactory quality is to be obtained. That is to say the alkyl aryl hydrocarbon chosen must be one which contains not more than 4%, and more preferably not more than about 2% by weight of impurities which are not sulfonated in the process. The sulfonatability can be determined readily, for instance, by testing a sample under the foregoing sulfonation conditions.

2

When the alkyl aryl hydrocarbons are produced by alkylation with pure olefins or other pure alkylating agents it is not difficult to obtain alkylates of the desired purity in high yields. But this is not the case when the alkylation is carried out with impure olefinic fractions containing olefins with different numbers of carbon atoms which are the more advantageous alkylating agents because of their lower cost and greater availability. In order to obtain alkyl aryl hydrocarbons having the desired sulfonatability from such alkylates it is necessary to remove impurities from the alkylates prior to sulfonation. This is commonly accomplished by careful fractionation of the crude alkylate. However, since the unsulfonatable impurities boil in the same range as the lower alkylates very sharp fractionation is required. That is the cut point must be so chosen that a considerable portion of the lower alkylates are distilled over with the impurities being removed. Since these lower alkylates form valuable alkyl aryl sulfonates, considerable loss in potential yield of detergent sulfonate is unavoidable in this method of operation.

When it is attempted to avoid this loss in yield of desirable sulfonates by postponing the removal of the unsulfonatable material until after the sulfonation step, great difficulties are encountered. The higher alkyl aryl sulfonates present in the usual alkyl aryl sulfonation mixtures are poorly soluble in water so that pastes are formed in the process. These can be purified only by using extremely high temperatures and/or dilutions which are undesirable. Besides adding to the cost of operation the high temperatures tend to cause discoloration of the final detergent product while high dilution involves increased expense due to the subsequent reconcentration which it makes necessary and even so usually permits only partial purification and results in products of inferior quality.

It is an object of the present invention to avoid the foregoing disadvantages in the production of alkyl aryl sulfonate detergents. More particularly it is an object of the invention to provide a process for producing mixtures of alkyl aryl sulfonate detergents and alkyl sulfate detergents more economically than is possible by the above-described prior method. A special object is the provision of a process whereby high yields of high quality alkyl aryl sulfonate detergent can be obtained economically from alkylates having relatively low sulfonatability.

Another object is the production of alkyl aryl sulfonate and alkyl sulfate detergent mixtures having especially advantageous properties. Other objects and advantages of the present invention will be apparent from the specification read in conjunction with the appended claims.

According to the invention alkyl aryl sulfonate detergents are produced by sulfonating alkylation products of aromatic hydrocarbons having a sulfonatability less than that which gives sulfonates of satisfactory surface active properties by the prior method, conversion of the products to alkyl aryl sulfonic acid salts and extraction of these salts in admixture with at least 10% by weight of the alkyl aryl sulfonic acid salt detergent content of alkyl sulfate salt detergent, with a solvent to remove unsulfonated components and obtain a detergent mixture of good quality. The addition of the alkyl sulfate detergent in the amount of at least 10% and preferably between about 20% and about 80% by weight to the alkyl aryl sulfonate results in a product which gives clear solutions in water and can be extracted successfully without resort to the undesirable high temperatures and/or dilutions which are required for extraction of the poorly soluble alkyl aryl sulfonates when treated alone.

Because the process of the invention in this modification enables the operator to use alkylates having a sulfonatability which is below the minimum of 96% which

has hitherto been considered necessary for the production of alkyl aryl sulfonates having desirable detergent properties and more advantageously considerably below such minimum, close fractionation of the alkylates is not essential. As a result of the yield of useful alkyl aryl sulfonate detergent product is considerably increased without any adverse effect on the final quality of the product. Thus through the use of alkyl sulfate detergent in the extraction step it becomes feasible to use wider boiling fractions of alkylated aromatic hydrocarbons in the sulfonation step and to increase the yield of high quality alkyl aryl sulfonate detergent. Alkyl benzene fractions having a sulfonatability not greater than about 90%, for example, are useful in the process.

The alkyl sulfate detergent which is used in the extraction step can be made in any of the usual ways. Suitable methods are described, for example, in U.S. Patents 2,139,393; 2,152,292; 2,172,228 and 2,618,649. The preferred alkyl sulfate detergents are water soluble salts, particularly the alkali metal, especially the sodium and/or potassium, or ammonium or amine salts of secondary alkyl sulfates having about 8 to about 18 carbon atoms per molecule. These alkyl sulfate detergents are advantageously produced by sulfating individual olefins or mixtures thereof having 8 to 18 carbon atoms by reaction with concentrated sulfuric acid, preferably of at least 85% concentration, more preferably 95% or higher concentration, at a temperature below about 100° C. and preferably of the order of about 10° to about 50° C. and neutralizing the resulting alkyl acid sulfate or mixture of such sulfates with a suitable base, for instance a hydroxide or carbonate such as sodium hydroxide or carbonate to form the desired water soluble salt which can then be recovered and purified in known ways.

It is an advantage of the present process in one of its preferred modifications, that the production of the secondary alkyl sulfate detergent can be combined with the manufacture of the alkyl aryl sulfonate detergent so as to substantially simplify the process and reduce the overall cost of the mixed alkyl aryl sulfonate-alkyl sulfate detergent product. Thus, the neutralization of the olefin sulfation product is preferably combined with the neutralization of the alkyl aryl monosulfonic acids obtained in the sulfonation step of the process and the mixed detergent salts thus obtained are desalted and extracted with a solvent to remove unconverted organic material especially hydrocarbon components remaining in the mixture.

Most advantageously the sulfation of the chosen olefin or olefin mixture is carried out with the reaction mixture obtained in the alkyl aryl hydrocarbon sulfonation step of the process. In this way the excess sulfonation agent which is necessary for satisfactory sulfonation of alkyl aryl hydrocarbons is used in sulfating the olefin or olefins. The sulfonation in this case is preferably carried out so that the concentration of sulfuric acid remaining on completion of the sulfonation is sufficient for the desired olefin sulfation. In order to obtain the highest yields it has been found to be advisable to employ oleum as the alkyl aryl hydrocarbon sulfonation agent, for example, oleum containing about 15% to about 30% free SO₃. Most preferably oleum is used in an amount to provide a mole ratio of SO₃ to alkyl aryl hydrocarbon of about 4 to about 7, preferably about 4 to 6, to 1. Temperatures in the range of about 10° to about 60° C. are desirable under these conditions. However, other sulfonation conditions which give sulfonation mixtures containing sulfuric acid of at least 85% and more preferably about 95% to about 102% concentration calculated on a hydrocarbon free basis can also be used. Thus an excess of oleum of higher or lower concentration or of sulfur trioxide or of sulfuric acid of high concentration can be used at temperatures in the range of about -10° to about 100° C. By appropriate

correlation with the reaction time using the stronger sulfonating agents at the lower temperatures and for shorter times good sulfonation can also be obtained.

The olefin or mixture of olefins of 8 to about 18 carbon atoms to be sulfated is added to the sulfonation with or without additional sulfuric acid in proportions such as to provide a mole ratio of sulfuric acid to such olefin of about 0.9:1 to about 2:1, more preferably about 1:1 to about 1.6:1. The mixture is advantageously reacted at about -10° to about 30° C. using a reaction time of the order of about 2 to 30 minutes although it will be recognized that the invention is not limited to the use of these conditions.

Surprisingly, it has been found that the yield of alkyl sulfate can be increased in this process by carrying out the sulfation of the olefins by means of the alkyl aryl hydrocarbon sulfonation mixture in the presence of an added diluent. Paraffins or mixtures of paraffins having 4 to 7 carbon atoms per molecule, such, for example, as normal butane, aromatic-free gasoline fractions, and the like, are particularly suitable diluents for this purpose. As a rule amounts of diluent between about one-half and five volumes per volume of olefin to be sulfated are suitable.

On completion of the sulfation step of the process, the mixture of alkyl aryl monosulfonic acid and secondary alkyl acid sulfate which is obtained is neutralized, preferably with an aqueous solution of a base of the type previously indicated, and the resulting solution of mixed alkyl aryl sulfonate-alkyl sulfate salt detergents is extracted as previously indicated to remove unsulfonated organic material comprising hydrocarbons, including saturated hydrocarbons, polymers, and unreacted alkylate and olefins, and like impurities which are detrimental to the surface-active properties of the product. Before extraction, however, it is usually advantageous to subject the mixture to a saponification treatment to convert any dialkyl sulfates present to monoalkyl sulfates. This can be accomplished by heating the neutralized mixture containing excess base, advantageously at about 80° to about 100° C. It is also generally preferable to treat the mixture of alkyl aryl sulfonate and secondary alkyl sulfate salt detergents to remove, at least in part, the inorganic sulfate, for example sodium sulfate, formed in the neutralizing step of the process from the unreacted sulfuric acid present. Such desalting can be carried out in any suitable manner. One such suitable method is by addition of an alcohol, for example, isopropyl alcohol, to precipitate out the inorganic sulfate before carrying out the extraction.

For the extraction of the unconverted organic material from the mixture of alkyl aryl sulfonate and secondary alkyl sulfate detergents in accordance with the invention, a solvent for this material which solvent is substantially insoluble in the aqueous detergent mixture is used. Hydrocarbon solvents are especially advantageous for this extraction. Suitable hydrocarbons include pure or substantially pure hydrocarbons such, for example, as benzene, toluene, pentane, hexane, diisobutylene, etc., as well as hydrocarbon mixtures such as gasoline and the like. It is preferable to choose hydrocarbons which may be readily separated by distillation from the extracts obtained in the purification step and to facilitate this they should most preferably have a boiling point or boiling range lower than that of the lowest boiling impurity which it is desired to remove. They should, preferably, not have too low a boiling point, however, as difficulties in recovery may be thereby incurred. The hydrocarbons preferably used in the process generally boil below about 160° C. and most preferably between about 70° C. and about 140° C., although lower or higher boiling hydrocarbons may in some cases be suitable depending upon the character of the impurities involved; thus even normally gaseous hydrocarbons may be used when the process is carried out under suitable superatmospheric pressure. It is of course feasible to use other types of solvents such, for

instance, as ethers or the like, but these are generally more expensive and offer no advantage over the preferred hydrocarbon solvents.

The extraction can be carried out in any of the conventional ways useful in liquid-liquid extraction. The solubilizing effect which the alkyl aryl sulfonate and secondary alkyl sulfate salt detergents have on each other avoids the need for undesirably high temperatures and/or dilution with water so that the extraction can advantageously be carried out at temperatures below 50° C. and preferably at ordinary room temperature directly with the product from the desalting step.

A special feature of the invention is the provision of a particularly advantageous modification of the process whereby more efficient use can be made of olefinic mixtures made up of olefins of 8 or 9 through 18 carbon atoms per molecule. Olefinic fractions of this kind can be produced on a large scale by cracking hydrocarbons. Vapor phase cracking of paraffin wax, for example, has been used as a source of olefins of 8 to 18 carbon atoms in producing secondary alkyl sulfate salt detergents. Pending application Serial No. 541,826, now Patent No. 2,871,254, describes the preparation of olefinic fractions of 8 to 18 carbon atoms which are especially suitable for the preparation of sulfated and sulfonated detergents according to the present invention. These fractions are produced by solvent extraction of catalytically cracked heavy cycle oil or mixtures of such cycle oil with slurry oil to remove aromatic constituents followed by vapor phase cracking of the raffinate. The olefinic fractions of 8 to 18 carbon atoms from these or other sources may be used in their entirety to prepare the alkyl aryl sulfonates and alkyl sulfate salt detergent. But in order to obtain detergents with the optimum surface-active properties by prior methods it has been found necessary to use only specific portions of these fractions. This, of course, involves a considerable loss in yield.

According to the present invention more advantageous use is made of olefinic mixtures which consist entirely or almost entirely of olefins having 8 or 9 to 18 carbon atoms per molecule, by splitting the mixture, for example by fractionation, into a lower boiling fraction of olefins of 8 or 9 to 12±1 carbon atoms per molecule and a higher boiling fraction of olefins of 13±1 to 18 carbon atoms per molecule and converting the lower boiling fraction into alkyl aryl sulfonates and the higher boiling fraction into secondary alkyl sulfate salt detergents. By carrying out the preparation of these alkyl aryl sulfonates and secondary alkyl sulfate salt detergents by the process of the present invention, the starting C₈ or C₉ to C₁₈ can be used in its entirety and loss of yield due to segregation of alkylate of high sulfonatability is avoided by taking advantage of the mutual solubilizing effect which the alkyl aryl sulfonate and secondary alkyl sulfate salts have on each other in the extraction step of the process.

A further advantage of this modification of the processes of the invention is that detergent mixtures can be produced having considerably better detergent, foaming and wetting properties than alkyl aryl sulfonates or alkyl sulfate detergents prepared from the entire C₈ or C₉ to C₁₈ olefin mixture. When, for example, a C₈ to C₁₈ sodium alkyl sulfate mixture was compared with a mixture prepared according to the invention, it was found that in the latter case the yield of active detergent material was increased from approximately 90% by weight to 134% by weight, calculated on the initial olefinic feed, while the foam number had increased from 20 to 27. The clear point (which is a measure of stability of the solutions against turbidity at low temperatures) of the mixture prepared according to the invention was also found to have improved. In 7% and 21% concentrations in water the clear point was 3° C. and 4° C. respectively, while the corresponding values for the C₈ or C₉ to C₁₈ alkyl sulfate mixture were 12° C. and 13° C. respectively. The

wetting properties had improved by over 100%, viz. from 100 to 219.

In order to obtain products having these desirable properties it is not necessary that the olefinic fractions be composed exclusively of olefins having the indicated ranges of carbon atoms, since small amounts, not more than about 5% of olefins with more or fewer carbon atoms can be present. Thus the C₈ or C₉ to C₁₂ or C₁₃ fraction may contain small amounts of C₇ or even C₆ olefins and C₁₄ olefins while the C_{13±1} to C₁₈ fraction may contain small amounts totaling less than 5% of C₁₁, C₁₂ and C₁₉ olefins including even traces of C₂₀ olefins. Also the proportions of C₈ or C₉ to C_{12±1} alkyl aryl sulfonate to C_{13±1} to C₁₈ alkyl sulfate water soluble salt in the product mixture can be varied although for the best detergent properties it has been found desirable to control the proportions so that the weight ratio of these detergents in the final product is approximately 65:35.

At a sacrifice in yield and economy the new detergent mixtures of C₈ or C₉ to C_{12±1} alkyl aryl sulfonates, particularly alkyl benzene sodium sulfonates with C_{13±1} to C₁₈ secondary alkyl sulfate salts, particularly the predominantly straight chain 2-alkyl sodium sulfonates, can be produced by other methods and these improved detergents especially when containing these components in the weight ratios of about 70:30 to 60:40 which give a desirable combination of surface-active properties are a feature of the invention regardless of their method of preparation.

It will be understood, moreover, that the process of the invention in its various modifications is not limited to the preparation of these especially valuable compositions but can be advantageously used in the manufacture of many other mixtures of alkyl aryl sulfonates and secondary alkyl sulfate salt detergents. Thus the sulfonates can be sulfonation products of alkylates obtained for example by reacting benzene, toluene, or other monocyclic aromatic hydrocarbons or mixtures thereof such, for instance, as aromatic extracts of mineral oils and the like, or naphthalene or methylnaphthalene, etc., with olefins or olefinic mixtures containing olefins of 8 to 20 or more carbon atoms per molecule. Detergent mixtures of such alkyl aryl sulfonates with water-soluble secondary alkyl sulfate salts which can be individual compounds or mixtures wherein the alkyl groups contain 8 to 20 or more carbon atoms are useful products of the new process. Especially useful products are, for example, obtained when alkylbenzene sulfonates made via alkylation with olefins of 8 or 9 to 12 to 13 carbon atoms are extracted in admixture with sodium alkyl sulfates from mixtures of olefins of 8 or 9 to 18 carbon atoms. Proportions of secondary alkyl sulfate salt detergents in the mixture can be as high as 80% by weight of the total alkyl aryl sulfonate and secondary alkyl sulfate salt detergent content and preferably is at least 30%. Especially advantageous products are obtained by using in the process mixtures of alkyl aryl sulfonates and secondary alkyl sulfate salts in ratios between about 60:40 and 20:80 when employing special combinations of these sulfonates and sulfate salts. These are mixtures of alkyl aryl sulfonates, preferably monoalkyl benzene monosulfonates, having 8 and/or 9 carbon atoms in the alkyl groups, preferably together with one or more alkyl aryl sulfonates, preferably monoalkylbenzene monosulfonates

having 10, 11, 12 or 13 carbon atoms in the alkyl groups and virtually free from alkyl aryl sulfonates having less than 8 or more than 13 carbon atoms in the alkyl groups, with mixtures wholly or almost entirely consisting of secondary alkyl sulfates having 8 or 9 to 18 carbon atoms per molecule. Such products can be readily obtained for example by adding a C₈-C₁₈ or C₉-C₁₈ fraction of olefins in controlled proportions to the sulfonation product of a C₈-C₉ alkylbenzene, for instance, and sulfating the added olefins, neutralizing the mixture, desalting and extracting as previously described.

The mixed alkyl aryl sulfonate and secondary alkyl sulfate salt detergents obtained by the process can be used as such in the form of aqueous solutions or can be dried and used as flakes or powders, etc. Builders such as pyro or polyphosphates, silicates, carbonates, and the like can be added, as can any of the various known foam stabilizers, washing agents, bleaching agents, etc. used with detergents of these types. Other detergents including alkyl aryl sulfonates and/or secondary alkyl sulfate salt detergents from other sources, or fatty acid soaps or non-ionic detergents or wetting agents or emulsifiers can be blended with the product for special purposes.

The invention is further illustrated by the following examples in which suitable methods for carrying out the new process are shown together with new compositions of the invention, it being understood that the invention is not restricted to the specific reactants, operations, conditions or compositions thus exemplified since these can be varied considerably without departing from the scope of the invention.

Example I

Benzene was alkylated in a stirred reactor with a C₈ to C₁₃ fraction of olefins obtained by vapor phase cracking of solvent refined catalytically cracked heavy hydrocarbon oil. The alkylation was carried out with hydrogen fluoride as catalyst using a volume ratio of hydrocarbon to catalyst phase of 1:1. The mole ratio of benzene to olefin was 10:1. The reaction was carried out at room temperature under a pressure of 4 atmospheres absolute using a stirring rate of 220 r.p.m.

After a residence time of 30 minutes the reaction was completed and the catalyst phase was then removed. The excess benzene was distilled off from the hydrocarbon mixture at atmospheric pressure, following which the remaining hydrocarbons were distilled at 40 mm. mercury pressure to separate a small amount of light and heavy ends and obtain a C₈-C₁₃ alkylbenzene alkylate which had a sulfonatability not exceeding 90%.

This alkylate was sulfonated at 55° C. with 20% oleum using a mole ratio of SO₃ to alkylate of 3:1. On completion of the reaction a small amount of water sufficient to reduce the concentration of sulfuric acid in the mixture to 65% to 75% was added whereby a sulfuric acid phase essentially free from alkylbenzene sulfonic acids was formed and decanted from the sulfonic acid phase.

A mixture of C₈-C₁₃ secondary alkyl sulfuric acid prepared by sulfating a C₈-C₁₃ fraction of olefins from hydrocarbon cracking with 98% sulfuric acid was added to the C₈-C₁₃ alkylbenzene sulfonic acids thus prepared in a weight ratio of 60:40. The mixture was then neutralized with excess sodium hydroxide and then heated to convert the dialkyl sulfates present into monoalkyl sulfates. To the saponified mixture there was added 25% of isopropyl alcohol and the resulting mixture was stratified and inorganic salts were separated. The thus desalted mixture of sodium C₈-C₁₃ alkylbenzene sulfonates and C₈-C₁₃ sodium secondary alkyl sulfates was extracted with gasoline which effectively removed the unconverted organic impurities giving a detergent mixture having excellent surface-active properties.

The yield of detergent thus obtained was 15% greater, calculated on the olefins, and 18% greater, calculated on the benzene, than that obtained in preparing the same mixture by blending corresponding amounts of the same C₈-C₁₃ alkylbenzene sodium sulfonates and C₈-C₁₃ secondary alkyl sodium sulfates separately prepared in the usual way.

Example II

A C₈-C₁₃ olefin mixture from the vapor phase cracking of paraffins was split by distillation into a C₈-C₁₂ and a C₁₃-C₁₈ fraction.

The C₈-C₁₂ fraction was used to alkylate benzene in virtually the same way as described in Example I, and

an alkylate was recovered having a sulfonatability of not more than 90%. The mixture obtained after sulfonating these C₈-C₁₂ alkylates as described in Example I, was then used for the sulfation of the C₁₃-C₁₈ fraction of the olefins.

The mixtures of benzene sulfonic acids and acid sulfates obtained in this way were neutralized, saponified, desalts and extracted with gasoline as described in Example I. The improvement in the yield obtained by the process of the invention was 15%, calculated on the olefins used, compared with that obtained by preparing the same C₈-C₁₃ alkylbenzene sulfonates and C₁₃-C₁₈ secondary alkyl sodium sulfates separately in the usual way and then blending them to produce a similar mixture.

The mixture thus obtained was compared in a number of foaming and wetting tests with a C₈-C₁₃ sodium secondary alkyl sulfate mixture from the same starting mixture of olefins having 8-18 carbon atoms in the molecule. The results are shown in the following table.

	C ₈ -C ₁₃ Secondary Alkyl Sulfates	C ₈ -C ₁₂ Alkyl Aryl Sulfonates + C ₁₃ -C ₁₈ Secondary Alkyl Sulfates in Ratio by Weight of 66:34

Example III

A C₈-C₁₃ olefin mixture, obtained by vapor phase cracking of refined heavy hydrocarbon oil obtained by C₈-C₁₁ and a C₁₂-C₁₈ fraction.

45 catalytical cracking, was split by distillation into a benzene was alkylated with the use of the C₈-C₁₁ fraction in substantially the same way as described in Example I. The alkylate was sulfonated at 55° C. with 50 oleum containing 23% of free SO₃, starting with a mole ratio of SO₃ to alkylate of 6.5:1. Towards the end of the sulfonation reaction the C₁₂-C₁₈ olefin fraction was added to the mixture and thus sulfated.

55 After neutralization and extraction with hydrocarbon to remove unconverted material and other hydrocarbon impurities, a mixture was obtained consisting of 56 parts by weight of alkyl aryl sulfonate and 44 parts by weight of alkyl sulfate. This mixture, as regards its desired properties, was also found to be considerably superior to the usual alkyl aryl sulfonate mixtures or alkyl sulfate mixtures, as is shown in the following table.

Example IV

The starting material was a C₈-C₁₈ cracked distillate fraction (boiling from 145° C. to 300° C.) from a thermal vapor phase cracked product of a raffinate obtained in the extraction of aromatics by means of furfural from a mixture of heavy cycle oil boiling between approximately 300° C. and 500° C. This material was, in turn, derived by fractionation of a liquid cracked product obtained by catalytic cracking of a mineral oil distillate boiling between approximately 300° C. and 500° C., and of the residual oil drawn off as bottom product in this fractionation. This C₈-C₁₈ cracked distillate fraction which had an alkene content of approximately 90% by weight was distilled to separate a C₈-C₁₃ fraction and a C₁₄-C₁₈ fraction.

The C₈-C₁₃ fraction was used to alkylate toluene employing sulfuric acid of 90% concentration as the catalyst in a volume ratio about equal to the volume of the hydrocarbon reactants and a mole ratio of toluene to olefins of 6:1. After reaction at 0° to 5° C. for about 70 minutes with vigorous stirring, the mixture was settled and the hydrocarbon layer decanted, neutralized, and distilled to remove excess toluene and light and heavy ends and obtain an alkylate fraction having a sulfonatability of less than 90%.

This alkylate was sulfonated with 20% oleum using a mole ratio of free SO₃ to alkylate of 3:1 and a temperature of about 45° C. for 40 minutes. On completion of the sulfonation, at which time the concentration of sulfuric acid in the reaction mixture was about 98% on an organic-free basis, the C₁₄-C₁₈ fraction of olefins was added to the mixture with continued stirring and cooling to about 0° to 5° C. About 0.6 mole of the olefinic mixture was added per mole of free sulfuric acid in the sulfonation product. After about 10 minutes' reaction time, the mixture was diluted with sufficient water to cause separation of a layer containing sulfuric acid of about 70% concentration which was drawn off and the mixture of C₈-C₁₃ alkyl-toluene sulfonic acids and C₁₄-C₁₈ secondary alkyl sulfuric acids remaining was neutralized with excess sodium hydroxide and the mixture heated to saponify the dialkyl sulfates present to alkyl sulfate sodium salts. The saponified mixture was then diluted with 25% of isopropyl alcohol and liquid phase desalting was carried out, following which the mixture was extracted with gasoline and the hydrocarbon impurities substantially removed.

The mixed C₈-C₁₃ alkyltoluene sodium sulfonate-C₁₄-C₁₈ secondary alkyl sodium sulfate detergents obtained containing sulfonate to alkyl sulfate detergent in a weight ratio of about 65 to 35 together with about 10% by weight of sodium sulfate, have somewhat lower foaming power than the corresponding product made by alkylating benzene but are good detergents. The yield based on olefins used is about 10 mole percent higher than is obtained when the active components are prepared separately in the usual way.

Example V

The following table gives the data relating to a number of tests for preparing mixtures of alkyl benzenes and sulfonates and secondary alkyl sulfates. The starting mixture of alkyl benzenes contained compounds with 10-14 carbon atoms in the alkyl group; the olefins used for the sulfation consisted of a mixture of olefins with 8-18 carbon atoms obtained from vapor phase cracked olefins with 8-18 carbon atoms obtained from vapor phase cracked paraffin waxes.

In each case the sulfonation was carried out with oleum of 25% concentration using a mole ratio of free SO₃ to alkylate of 5:1 and a reaction time of 30 minutes at 55° C. The sulfation was then effected by adding the C₈-C₁₈ fraction of olefins to the sulfation mixture with or without pentane as diluent as shown in the table and stirring for 10 minutes at 0° C., except in the

first two runs which were conducted at 10°-15° C. and about 5° C., respectively. The sulfonation yield was 98% in each case. The products recovered after neutralization with sodium hydroxide and removal of undesirable hydrocarbon impurities as previously described had excellent surface-active properties and were obtained in substantially improved yields compared with separate preparation of the C₁₀-C₁₄ alkylbenzene sodium sulfonate and C₈-C₁₈ secondary alkyl sodium sulfate components.

15	Sulfation		Volume Ratio, Pentane to Cracked Wax Olefins	Mole Ratio, Alkylate to Cracked Wax Olefins	Sulfation Yield, percent	Ratio by Weight of Sulfonate to Sulfate in Final Product

* Calculated without taking into account the dilution with sulfonic acid.

** After sulfonation oleum of 60% was added in order to increase the H₂SO₄ concentration from 97.9% to 100.9%. The same result can be obtained by sulfonating with a mole ratio of alkylate : SO₃ of 1: 6.66.

We claim as our invention:

1. A process for producing a mixture of alkyl aryl sulfonate and secondary alkyl sulfate salt detergents which comprises sulfonating an alkyl aryl hydrocarbon fraction having alkyl groups of at least 8, and not more than 20, carbon atoms, and a sulfonatability of less than 96% due to impurities which are not converted to desirable alkyl aryl sulfonic acid during the sulfonation and reduce the surface activity of the alkyl aryl sulfonate detergent obtained on neutralization of the sulfonation product, extracting the aqueous neutralized sulfonation product in the presence of at least 10%, based on the weight of said alkyl aryl sulfonate, of secondary alkyl sulfate salt detergent, containing 8 to 18 carbon atoms per molecule, with a hydrocarbon solvent for said impurities, said solvent boiling within the range of from about 70° to about 160° C., and being substantially insoluble in the aqueous solution of said secondary alkyl sulfate salt detergent-containing neutralized sulfonation product, whereby removal of impurities is effected and a detergent mixture having improved surface-active properties is obtained.
2. A process in accordance with claim 1 wherein an alkyl benzene fraction having alkyl groups of at least 8 carbon atoms and not more than 18 carbon atoms and a sulfonatability not greater than about 90% is sulfonated and the extraction is carried out with hydrocarbon boiling between about 70° C. and about 140° C.
3. A process for producing a mixture of alkyl aryl sulfonate of the benzene series and secondary alkyl sulfate salt detergents wherein said alkyl groups contain not less than 8 nor more than about 18 carbon atoms, which comprises sulfonating an alkylation product of a hydrocarbon of the benzene series corresponding to said sulfonate and having a sulfonatability not greater than about 90%, adding to the resulting alkyl aryl monosulfonic acid product secondary alkyl sulfuric acid corresponding to said alkyl sulfate salt in an amount between about 30% and about 80% of the total weight of said monosulfonic acid and alkyl sulfuric acid, neutralizing and desalting the mixture and extracting unreacted hydrocarbon impurities therefrom with a hydrocarbon solvent for said impurities boiling within the range of from about 70° C. to about 160° C. to obtain a high yield of detergent having desirable surface-active properties.
4. A process for producing a mixture of monoalkylbenzene sodium sulfonate and secondary alkyl sodium sulfate detergents which comprises sulfonating a mono-

11

alkylbenzene fraction having a sulfonatability not greater than about 90% wherein the alkyl groups contain not less than 8 nor more than about 18 carbon atoms with an excess of sulfonating agent, adding to the alkylbenzene monosulfonic acid-containing reaction mixture at least one olefin of 8 to 18 carbon atoms per molecule, maintaining the mixture under sulfating conditions until substantial reaction of said olefin has taken place, neutralizing the resulting mixture of sulfonic acid and secondary alkyl sulfuric acid with a basic sodium compound, separating inorganic salt formed in the neutralization step from the sodium sulfonate and secondary alkyl sulfate salts produced and extracting the mixture with a gasoline fraction boiling in the range of about 70° C. to about 140° C. to remove hydrocarbon impurities therefrom.

5. A process in accordance with claim 4, wherein the sulfonation is carried out with an amount of oleum such that the sulfonation mixture contains sulfuric acid of at least 95% concentration on an organic free basis on completion of the sulfonation step.

6. A process in accordance with claim 5 wherein the sulfation is carried out in the presence of an added paraffin diluent having 4 to 7 carbon atoms per molecule.

7. A process in accordance with claim 5 wherein the sulfation is carried out with a mole excess of sulfuric acid based on said olefin.

8. A process for producing a detergent mixture, comprising alkylating benzene with a fraction of olefins from hydrocarbon cracking containing olefins of 8 to 9 carbon atoms per molecule and essentially free from olefins of more than 13 carbon atoms, sulfonating the resulting alkylate having a sulfonatability not greater than about 90% to produce predominantly monoalkylbenzene monosulfonic acids, converting said sulfonic acids to water soluble monoalkylbenzene sulfonate salts and extracting said sulfonate salts with a liquid hydrocarbon boiling between about 70° C. and about 160° C. in the presence of C₈ to C₁₈ secondary alkyl sulfate salts in an amount equal to 40% to about 80% of the total weight of said monoalkylbenzene sulfonate salts and said secondary alkyl sulfate salts in the mixture.

9. A process for producing a mixture of water soluble alkylbenzene sulfonate detergent salt and secondary

alkyl sulfate salt detergent which comprises fractionating a mixture of olefinic products of hydrocarbon cracking containing olefins of 8 to 9 through 18 carbon atoms per molecule, to separate a lower boiling fraction containing the C₈ to C₉ through the C₁₁ to C₁₃ olefins from a higher boiling fraction containing the remainder of the olefins of said starting mixture, alkylating benzene with said lower boiling fraction, sulfonating resulting alkylate having a sulfonatability not greater than about 90%, neutralizing the monoalkylbenzene sulfonic acids thus produced to form said water soluble alkylbenzene sulfonate detergent salt, and extracting said alkylbenzene sulfonate detergent salt in admixture with water soluble secondary alkyl sulfate salt detergent produced by sulfating said higher boiling fraction of olefins and neutralizing the secondary alkyl sulfuric acids so obtained, said extraction being carried out with a hydrocarbon solvent for hydrocarbon impurities present in the mixture which reduce the surface-active properties thereof whereby substantial removal of said impurities is effected said hydrocarbon solvent boiling between about 70° C. and about 140° C.

10. A process in accordance with claim 9 wherein the neutralization of the secondary alkyl sulfuric acids is carried out by adding a base to a mixture of said alkylbenzene sulfonic acids and said alkyl sulfuric acids in weight ratios of 70:30 to 60:40.

11. A process in accordance with claim 10 wherein the higher boiling fraction of olefins is added to said sulfonation mixture and the sulfation of the olefins effected therein.
